UNITED STATES PATENT OFFICE.

THOMAS JOSHUA ROBERTS, OF ATLANTA, GEORGIA.

APPARATUS FOR CRANKING AUTOMOBILES.

1,004,201.

Specification of Letters Patent. Patented Sept. 26, 1911.

Application filed May 16, 1911. Serial No. 627,524.

To all whom it may concern:

Be it known that I, THOMAS J. ROBERTS, a citizen of the United States, residing at Atlanta, in the county of Fulton and State 5 of Georgia, have invented certain new and useful improvements in Apparatus for Cranking Automobiles; and I do hereby declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to new and useful improvements in apparatus for cranking automobiles and the object in view is to produce a simple and efficient device of this nature which may be actuated by an operator 20 while sitting in the seat of the machine and comprises various details of construction and combinations and arrangements of parts which will be hereinafter fully described 25 and then specifically defined in the appended claims.

I illustrate my invention in the accompanying drawings, in which:—

Figure 1 is a sectional view through an 30 automobile showing the application of my invention. Fig. 2 is a cross sectional view. Fig. 3 is a section on line 3—3 of Fig. 2, showing parts in elevation, and Fig. 4 is a detail sectional view.

Reference now being had to the details of the drawings by letter, A designates a portion of the front end of an automobile and B is a motor shaft which is journaled in suitable bearings and has a series of ratchet 40 teeth B' formed in the end thereof. Fas- tened to the forward end of the part A of the automobile is a cylindrical outlined member C, the inner end of which is closed and centrally apertured for the reception of 45 the end of the motor shaft having said ratchet teeth. Upon reference to the sec- tional view in the drawings, it will be noted that the forward end of the motor shaft ex- tends only partially through the aperture in 50 the end of the cylinder. Said cylinder has, at any suitable location, ribs C' projecting therefrom which, in the present instance, are located diametrically opposite each other. Springs, designated by letter E, are adapted 55 to bear yieldingly against the inner face of the disk F, and the bottom of the recess in

the cylinder. The disk F is centrally aper- tured at F' for the reception of the false 60 shaft G, which has ratchet teeth G' formed at its inner end adapted to intermesh with the ratchet teeth and the outer end of the motor shaft. The inner end of the shaft G is adapted to have a bearing in the central aperture formed in the end of the cylinder and, when at its farthest inner throw, is in 65 gear with the ratchet teeth of the motor shaft. Said disk F has notches F² formed in its circumference at points diametrically opposite and adapted to receive said ribs C', the latter and said recesses forming means 70 for guiding the disk as it is moved back and forth within the cylinder. The outer face of the disk is provided with a hub I which is centrally apertured and the false shaft has a bearing in the registering apertures in the 75 disk and hub. The outer end of the shaft G has a bearing in a cross-piece J which is sup- ported by the arms H which project in ad- vance of the forward end of the automobile. Fixed to the false shaft is a gear wheel O, 80 the teeth of which are adapted to having sliding mesh with the teeth of a gear wheel K which is fastened to the rotatable shaft L. Said shaft is journaled in suitable bearings 85 in the frame of the automobile and has con- nected therewith an operating wheel L', which is so positioned as to be within con- venient reach of the operator of the automobile as he sits upon the seat of the machine. The outer face of the gear wheel O is pro- 90 vided with a recess O', the ends of which are inclined, and Q designates an anti-friction wheel which is journaled upon a pin Q' car- ried in the recess in the cross-piece J. Said anti-friction wheel is adapted to be normally 95 positioned in the recess formed in the outer face of the gear wheel O when the apparatus is at rest, the parts being held in such posi- tion by the springs upon the inner end of the cylinder which bear against and hold 100 the disk at its farthest outer limit.

When it is desired to start the engine by cranking the same for the purpose of draw- 105 ing in a compression preparatory to its be- ing exploded, the operator, by giving the hand wheel a partial rotary movement, may cause a complete revolution to be imparted to the gear wheel O, intermeshing with the wheel K. It will be noted that the compar- ative size of the gear wheels will cause the gear wheel O to make a complete revolution 110 while the hand wheel is only given a partial

revolution. As the gear wheel O commences to rotate, the inclined end of the recess coming against the anti-friction wheel will cause the gear wheel to be moved toward the engine under the tension of the springs which bear against the inner face of the disk. After the anti-friction wheel leaves the recess, it will contact against the outer face of said gear wheel and, when a complete revolution is imparted to the gear wheel O and the anti-friction wheel comes opposite the recess, the springs bearing against the disk will cause the gear wheel to be thrown back to its normal position. As the gear wheel O is thrown toward the engine in the manner described, the ratchet teeth at the inner end of the false shaft upon which the same is mounted will intermesh with the teeth upon the outer end of the motor shaft and cause the same to rotate and draw into the engine and compress a charge in the usual manner.

From the foregoing, it will be noted that, by the provision of a cranking apparatus as shown and described, a simple and efficient means is afforded whereby the engine may be conveniently started without the necessity of the person putting on the usual crank which is commonly the custom and, afterward getting into the vehicle, the cranking, by the present invention, being conveniently accomplished by the operator while sitting in his seat upon the machine.

What I claim to be new is:—

1. An apparatus for cranking automobiles comprising a motor shaft with ratchet teeth in the end thereof, a spring-pressed block, means for guiding the same, a false shaft journaled in said block and having ratchet teeth at its inner end adapted to engage the teeth of the motor shaft, a gear wheel fixed to the false shaft, a hand operated wheel, gear connection between the same and the gear upon the false shaft, said gear wheel upon the false shaft having a recess in its face, an anti-friction wheel mounted adjacent to the gear wheel and normally positioned in said recess, said false shaft adapted to be given a longitudinal movement to cause the ratchet teeth to intermesh as the gear wheel is rotated.

2. An apparatus for cranking automobiles comprising a motor shaft with ratchet teeth in the end thereof, a casing secured to the forward end of the automobile and having a closed end which is apertured for the reception of the end of the motor shaft, a block movable within the casing, means for guiding the block, said block having a central aperture, springs fastened to the inner end of the casing and bearing against said block, a false shaft journaled in an

aperture in the block and having ratchet teeth at its inner end adapted to intermesh with the ratchet teeth of the motor shaft, a hand operated wheel and gear connections between the same and the false shaft for rotating the latter, and means for imparting a longitudinal movement to the false shaft as the gears rotate.

3. An apparatus for cranking automobiles comprising a motor shaft with ratchet teeth in the end thereof, a casing secured to the forward end of the automobile and having a closed end which is apertured for the reception of the end of the motor shaft, a block movable within the casing, means for guiding the block, said block having a central aperture, springs fastened to the inner end of the casing and bearing against said block, a cross-piece upon the frame of the automobile, a false shaft having a bearing in said cross-piece and in said block and having ratchet teeth formed in its inner end, a gear wheel fixed to the false shaft and having a recess in its outer face, an anti-friction wheel carried by the cross-piece and normally positioned in said recess, a hand operated wheel, a shaft carrying the same, and gear connections between the shaft and gear wheel with the recess in the face thereof.

4. An apparatus for cranking automobiles comprising a motor shaft with ratchet teeth in the end thereof, a cylindrical casing fastened to the end of the automobile and having an inner wall which is apertured for the reception of the motor shaft, ribs projecting from the circumference of said casing, a block movable within the casing and having notches for the reception of said ribs, springs fastened to the inner face of the end wall of the casing and bearing against said block, a cross-piece upon the frame of the automobile, a false shaft journaled in said cross-piece and in an aperture in said block, the inner end of the false shaft having ratchet teeth, a gear wheel fixed to the false shaft and having a recess in its outer face, the inner walls of which are inclined, an anti-friction wheel journaled in the cross-piece and normally positioned in said recess, a hand operating wheel, a shaft upon which the same is mounted, a gear wheel fixed to the shaft upon which the operating wheel is mounted and in mesh with said gear wheel upon the false shaft.

In testimony whereof I hereunto affix my signature in the presence of two witnesses.

THOMAS JOSHUA ROBERTS.
